OLIVE GRADING MACHINE

Louis B. Sammis and Frank R. Hood,
Wallace, Calif.

Application April 12, 1948, Serial No. 20,445

2 Claims. (Cl. 209—102)

1

This invention is directed to, and it is an object to provide, a novel and improved olive grading machine, of flexible cable type, adapted to grade olives for size.

While the invention is here described as used as a size grader for olives, it is understood that its use is not so limited, and it may also be used effectively to so grade other produce or objects.

Another object of the invention is to provide an olive grading machine which comprises a plurality of cable runs disposed in parallel but spaced relation in a horizontal plane, but with the intermediate one of each three adjacent runs diverging downwardly in a vertical plane in the direction of travel whereby, in effect, providing an olive reception and grading trough having longitudinal side openings of increasingly greater width for the passage therethrough at different points of olives of corresponding size whereby effective size grading is accomplished.

An additional object of the invention is to provide an olive grading machine, as in the preceding paragraph, which is arranged for adjustment of the cable runs to increase or decrease the extent of said divergence, dependent on the general size of the variety to be graded, and the size grading desired.

A further object of the invention is to provide an olive grading machine which has a high hourly capacity, without the machine being of undue width or length.

It is also an object of the invention to provide an olive grading machine which is relatively simple and inexpensive in structure, and designed so that the cable wear is minimized.

Another object of the invention is to provide an efficient olive grading machine adapted to grade all varieties of olives, regardless of general size or shape.

A further object of the invention is to provide a practical and reliable olive grading machine, and one which will be exceedingly effective for the purpose for which it is designed.

These objects are accomplished by means of such structure and relative arrangement of parts as will fully appear by a perusal of the following specification and claims.

In the drawings:

Fig. 1 is a longitudinal sectional elevation of the machine.

Fig. 2 is a plan view of the machine.

Fig. 3 is a diagrammatic view of the cable system.

Fig. 4 is a diagrammatic cross section, on line 4—4 of Fig. 1, of the working runs of the cable.

Fig. 5 is a diagrammatic cross section on line 5—5 of Fig. 1 of said working runs of the cable.

Referring now more particularly to the characters of reference on the drawings, the nu-

2

meral 1 indicates an upstanding elongated main frame. This main frame 1 supports, at the top thereof, a size grading table, indicated generally at 2; such size grading table being of the type which includes a plurality of longitudinal cable runs supported and actuated in the manner hereinafter described.

The size grading table 2 runs in the direction indicated by the arrow in Fig. 1, and between upstanding longitudinal side plates 3.

The ungraded supply of olives is fed from a hopper (not shown) by means of a chute 4 onto the lead end of the size grading table 2, and olives as graded by said table fall into certain ones of a longitudinal row of receiving bins 6 having bottoms sloping laterally to feed the various grades of the olives from the machine onto corresponding feed belts or the like (not shown). The bins 5 are defined in part by transverse partitions 7 which may be adjustable lengthwise of the machine to vary the grade or olive size received by each bin; the grading table 2 functioning, as will hereinafter appear, to grade the olives progressively from the smaller to the larger sizes lengthwise of the machine.

The size grading table 2 embodies the major feature of the invention, and is constructed and operates as follows:

Beyond opposite ends of the row of bins the main frame 1 supports cross shafts 8 and 9; said cross shafts being in substantially the same horizontal plane, and at least one of said shafts being driven to impart rotation thereto in the indicated direction.

Outwardly of the cross shaft 9 the machine includes another cross shaft 10, which is vertically adjustably mounted by means of a longitudinally extending, generally U-shaped yoke 11 which straddles the grading table and is pivoted at its free ends, as at 12, to the cross shaft 8 for vertical adjustment.

The cross shaft 10 is journaled on the yoke 11 adjacent but short of the forward or closed end 13 of the yoke. An upstanding adjustment screw 14 is mounted in connection with the closed end 13 of the yoke and bears against a plate 15 fixed in connection with the main frame 1.

By adjustment of the screw 14 in one direction or the other, the yoke 11 is raised or lowered to correspondingly raise or lower the cross shaft 10 relative to the horizontal plane in which the cross shafts 8 and 9 are disposed. The cross shaft 10 normally occupies a vertically adjustable position somewhat below said horizontal plane of the cross shafts 8 and 9, as clearly shown in Fig. 1.

Between the side plates 3 the cross shaft 8 is fitted with a plurality of side by side cable sheaves 16. Corresponding sheaves are provided at the opposite end of the machine, but are mounted

alternately on the cross shaft 9 and cross shaft 10; the sheaves on the cross shaft 9 being indicated at 17, and the sheaves on the cross shaft 10 being indicated at 18. The sheaves 17 and 18 are in direct alinement longitudinally of the machine with corresponding ones of the sheaves 16.

A single endless length of cable is reeved back and forth in the machine between the sheaves 16 and the corresponding sheaves 17 or 18 at the opposite end of the machine, whereby to provide a plurality of longitudinally extending upper cable runs, indicated generally at 19. The upper cable runs are thus parallel in a horizontal plane, and spaced apart, transversely of the machine, an equal distance.

It will be observed, however, that as the cross shaft 10 is below the cross shafts 8 and 9, those of the upper cable runs 19 which travel on the sheaves 18 diverge downwardly relative to the upper cable runs 19 which traverse the sheaves 17. The extent or angle of such divergence is of course variable by adjustment of the yoke 11 by means of the adjusting screw 14.

With the above arrangement, each three adjacent cable runs 19, comprising a pair 20 on sheaves 17 and an intermediate run 21 on an intermediate sheave 18, form a longitudinal, olive reception and grading trough, indicated diagrammatically at 22. Each such trough 22, as defined by three lengthwise cable runs, includes longitudinal side openings 23 which increase in width lengthwise of the machine from its head or starting end.

As the olives feed from the chute 4 onto the described size grading table 2, which travels in the direction indicated by the arrow in Fig. 1, said olives fall into the grading troughs 22 and travel along therewith until the ever-increasing width of the side openings 23 permits the olives to escape from the cables and drop into the receiving bins 5. The partitions 7 are set so that olives of predetermined size fall into certain ones of the bins.

The action of the size grading table 2 will be thus fully understood, particularly upon examination of Figs. 4 and 5. The ever-increasing divergence of the intermediate cable runs 21 relative to the corresponding pair of horizontal cable runs 20 of each trough 22 produces an effective size grading of the olives as they travel along the table 2; the smaller sizes being graded out first, followed by olives of ever increasing size.

The design of the machine, particularly with respect to the cable type size grading table 2 is such that it works in a practical and effective manner on all types of olives, whether the round type or the oblong type; it being interesting to note that oblong type olives, once in the grading troughs 22, roll end over end lengthwise while riding the intermediate cable run 21, until the side openings 23 permit their escape. In this manner grading of oblong olives, heretofore a problem, is accomplished with a minimum of variation from grade.

In order to maintain the cable system taut, opposite leads 24 are carried away from the pulley assembly over suitable direction changing sheaves 25, and thence the cable passes about the sheave of a tensioning unit 26 located in the main frame 1, as shown.

In order to prevent any undesirable side play of the upper cable runs 19 they are supported, intermediate their ends, by idler sheaves 27 and 28.

The idler sheaves 27 are journaled on a fixed cross shaft 29 which extends between the side plates 3, and said sheaves 27 carry the cable runs 20 which extend between the sheaves 16 and 17. The sheaves 28 are carried on a cross shaft 30 which is mounted, at its ends, in connection with the legs of the yoke 11, whereby to rise and fall with the latter; said sheaves 28 carrying the intermediate cable runs 21, which extend between the sheaves 16 and the sheaves 18.

The above described olive grading machine provides for very practical and accurate size grading of olives, accomplishing the result by means of a grading table which is not excessive in length or in width. Additionally, the adjustment of the grading table for handling olives of generally different sizes, or for accomplishing grading of predetermined sizes at different points lengthwise of said table, requires only a simple manual adjustment of the screw 14.

From the foregoing description it will be readily seen that there has been produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent are desired:

1. A grading machine comprising a supporting frame, a pair of shafts journaled on the frame and spaced apart longitudinally thereof to provide a first shaft and a second shaft, said shafts lying in substantially the same horizontal plane, sheaves fixed to the first shaft in transversely spaced apart relation, a sheave fixed on the second shaft disposed in alinement with each alternate sheave on the first shaft, a substantially U-shaped yoke, said yoke straddling the supporting frame and having the free ends of its arms pivoted on the first shaft, the closed end of said yoke being disposed at a point outwardly of the second shaft, a third shaft mounted in the yoke outwardly of the second shaft and lying in a lower horizontal plane with respect thereto, a sheave fixed on the third shaft in alinement with each of the sheaves on the first shaft which lie between the sheaves with which the sheaves on the second shaft are alined, a driven belt extending about each pair of alined sheaves, and means for vertically adjusting the position of the yoke about its journal axis.

2. A machine as in claim 1 in which said last named means comprises a vertically disposed adjustment screw threaded through the closed end of the yoke and impinging at its lower end against a part of the supporting frame.

LOUIS B. SAMMIS.
FRANK R. HOOD.
